GEORGE B. THOMAS, OF BRIDGEPORT, CONNECTICUT, ASSIGNEE TO THE BRYANT ELECTRIC COMPANY, OF BRIDGEPORT, CONNECTICUT, A CORPORATION OF CONNECTICUT.

ATTACHMENT-PLUG AND RECEPTACLE.

1,205,683.

Specification of Letters Patent. Patented Nov. 21, 1916.

Application filed October 21, 1915. Serial No. 57,123.

To all whom it may concern:

Be it known that I, GEORGE B. THOMAS, a citizen of the United States of America, and residing in the city of Bridgeport, county of Fairfield, and State of Connecticut, have invented a certain new and Improved Attachment-Plug and Receptacle, of which the following is a specification.

My invention relates to attachment-plugs and particularly to certain details of construction which constitute improvements over that now commonly in use.

In the accompanying drawings, Figure 1 is a horizontal section through an attachment plug and receptacle in which my invention is embodied in one form; Fig. 2 is a plan of the receptacle alone; Fig. 3 is an inverted plan of the same partially broken away; Fig. 4 is a cross section on the lines 4-4, Fig. 2; Fig. 5 is a perspective of one of the receptacle terminals; Fig. 6 is a cross section on the line 6-6, Fig. 2; Fig. 7 is an inverted plan of the attachment plug alone; and Fig. 8 is a plan of the insulating disk for the plug.

As here illustrated, my invention is embodied in a plug and receptacle of the fixed polarity type. The receptacle comprises a body 10 of insulating material having depressed ledges 11 on diagonally opposite corners, on which the wire terminal plates 12 are secured by the screws 13 piercing the base from below and taking into tapped holes in the terminal plates. Metallic yoke ears 14 at each end of the body afford means for mounting the receptacle in an outlet box (not shown) and also for securing in position the face plate 15. A flat annular boss 16 may be formed on the upper surface of the receptacle, which boss projects through or into a central aperture formed in the face plate to receive it. Within the area of this boss the body of the receptacle is pierced by two slots 17 and 18 lying at right angles to each other. The two receptacle terminals 19 and 20 project upward into these slots from the straps 21 and 22 to which they are secured by rivets 23 and to which current is conducted from the wire terminals 12 by the screws 13 which extend from the latter to straps 24 and 25 let into the lower face of the body 10 and underlying the straps 21 and 22. These latter straps are electrically connected to the

straps 24, 25, and also held in position in their channels in the lower face of the body 10, by means of counter-sunk screws 26, 27, passing downward through the body 10, slots 28 in the ends of straps 24, 25 and taking into tapped holes in the straps 21, 22.

In the finished device the heads of the screws 26, 27, are covered with insulating wax and likewise the straps 21, 22, and 24, 25, lying in the channels in the lower face of the porcelain body 10. There is some danger however that the wax will shrink or otherwise become loose from the body 10 as it hardens and that it will fall out, thus exposing the live conductors which it is designed to cover. To obviate this trouble I have struck anchoring lugs or projections 29 from the overlying straps 21 and 22. When the wax is flowed in molten condition into the strap channels, it works beneath the anchor lugs 29 and the latter retain the wax after it has hardened, even should it loosen from the walls of the channels.

Coöperating with this receptacle I provide an attachment plug which comprises a body 30 of insulating material pierced at 31 to admit the leading-in wires (not shown). Depressed wells form seats shaped to the bases 32, 33, of the plug jacks 34, 35, 36 in the form of blades lying at right angles to each other and spaced apart in proper relation to the holes 17 and 18 in the receptacle so that they freely enter the latter and engage the receptacle terminals 19, 20. Binding screws 36 on the bases 32, 33, afford means for securing the bared ends of the leading-in wires, while securing screws 37 hold the jack bases firmly in their wells. In the fully inserted position of the plug, the shallow depressions 38 formed in the faces of the jacks are engaged by the teats 39 on the contact faces of the receptacle terminals, and a spring engagement between the parts is thus established which prevents the accidental withdrawal of the plug. In order to form a closed wiring chamber, I provide an insulating disk 40 of stiff paper or fiber which is provided with slots 41, 42 lying at right angles to each other and in register with the jacks 34 and 35 so that it may be passed down over the jacks and seated on the shallow ledge 43 formed within the narrow peripheral rim 44 on the entering face of the plug. In order to be able

to remove the disk, this rim is notched out at 45° on opposite sides of the plug, so that the finger nails or the end of a screw driver may be passed beneath the inner face of the disk to lift the same away from the plug body. A metallic casing 46 is fitted on the insulating body of the plug and spun into the wire hole 31 at one end and over the edge of the rim 44 at the other end, thus securing it permanently on the plug.

The construction shown is economical of material yet rugged in construction, while its metal parts are readily made and easily assembled.

15 Variations in detail, which do not depart from what I claim as my invention, will readily suggest themselves to those skilled in the art.

I claim as my invention:—

20 1. An electrical device of the type described comprising an attachment plug receptacle having a one-piece insulating body pierced by slots, wire terminals on diagonally opposite corners of the outer face of the block, conducting straps let into recesses on the opposite face of the block and underlying the wire terminals, screw means electrically and mechanically connecting said straps and wire terminals and securing the 25 same upon said block, together with receptacle terminals carried by and wholly supported from said straps and projecting into said slots, and supplemental means piercing the blocks for securing said straps thereto 30 and holding the receptacle terminals in position in their slots, substantially as described.

35 2. In an electrical device, a block of insulation having a channel in a face thereof, a conducting strap lying in said channel, an anchor lug struck from said strap and an 40 insulating composition covering said strap in the channel and engaging said anchor lug on all sides whereby said composition is held

in the channel by said anchor lug on the strap.

3. An electrical device of the type described, comprising an attachment plug having an insulating block recessed on one face to form a wiring chamber, plug jacks secured at one end within said chamber and projecting beyond the face of the block, and wire terminals electrically connected to said jacks within the wiring chamber, said face of the block having a marginal rim and a shallow ledge inwardly offset therefrom, in combination with an insulating disk slotted in register with said jacks and fitting within said rim and against said ledge with the jacks passing through said slots in the assembled position of the parts, substantially as described.

4. An electrical device of the type described, comprising an attachment plug having an insulating block recessed on one face to form a wiring chamber, plug jacks secured at one end within said chamber and projecting beyond the face of the block, and wire terminals electrically connected to said jacks within the wiring chamber, said face of the block having a marginal rim and a shallow ledge inwardly offset therefrom, in combination with an insulating disk slotted in register with said jacks and fitting within said rim and against said ledge with the jacks passing through said slots in the assembled position of the parts, said rim being notched out at predetermined points to afford access to the edge of the insulating disk for the removal of the latter.

In testimony whereof I have signed my name to this specification, in the presence of two subscribing witnesses.

GEORGE B. THOMAS.
